FLYING MACHINE

Application filed October 12, 1926, Serial No. 141,203. Renewed March 19, 1929.

My invention relates to the heavier-than-air type of flying machine and has among its salient objects to provide a flying machine which is capable of rising substantially vertically in the air from a condition of rest; to provide means for holding the machine upright and in a horizontal position during flight, even when passengers move around in it; to provide such a machine which is capable of being steered in any direction; to provide a machine of the character referred to which can have its direction of travel reversed so that it can move either forwardly or rearwardly, as may be desired by the operator; to provide a flying machine which will have a gradual descent in case the motor or motors stop; and, in general, to provide a new type of heavier-than-air flying machine with means for automatically maintaining it on an even keel and with means for manually controlling the same.

In order to explain my invention, I have illustrated one embodiment thereof on the accompanying three sheets of drawings, 25 which I will now describe.

Figure 1 is a perspective view of a flying machine embodying my invention from above;

Figure 2 is a perspective view of the same from beneath said machine;

Figure 3 is a front end view thereof;

Figure 4 is a vertical, cross sectional view taken on a position indicated by the line 4-4 of Fig. 7;

Figure 5 is an axial sectional view through one of the electric clutch elements;

Figure 6 is a fragmentary sectional view showing one of the vanes with operating connections for moving the same;

Figure 7 is a vertical, longitudinal sectional view at the position indicated by line 7-7 of Fig. 3; and

Figure 8 is a view to show in details the driving connections and the automatic electrical control mechanism.

Referring now in detail to the drawings, my invention as illustrated for descriptive purposes, comprises a long box-like body, 10, tapering and closed at its opposite ends, 50 as at 11. On its opposite sides, extending

longitudinally thereof are two fixed wings, 12 and 13, of substantially the form illustrated in cross section and of light hollow construction as indicated in Fig. 4, said wings being convexed upwardly in their main portion transversely and turned upwardly at their outer edges for the entire length thereof to insure a more steady descent should the motor stop. There is also provided forwardly and rearwardly of said longitudinally extending wings two pairs of planes, 14, 14 and 15, 15, mounted to be rotated axially to raise and lower their forward and rearward edges.

Said box-like body, it will be seen, is positioned diagonally in cross section, relative to the vertical, so that one corner thereof is the highest part, while at opposite sides thereof and between said corner line and said fixed wings, 12 and 13, are two triangular shaped compartments, extending longitudinally of the machine, and designated 16 and 17. In the top wall of these compartments, forwardly and rearwardly of each, are openings or air shafts, 18, 19, 20 and 21, in which are control dampers or shutters, 18', 19', 20', 75 and 21', mounted to turn on their axes and each group being connected to move together and all four groups being controlled and operated in a manner hereinafter again referred to.

Directly beneath each of said groups of shutters, or dampers, is a corresponding set positioned transversely of the set above and connected for manual control. Referring to Fig. 4, directly beneath the groups of shutters, 18' and 19', are the transverse shutters, designated, 22 and 23, the shutters of each group being connected together, as at 24, and the two groups being connected by a common shaft, 25, provided with an operating arm, 26, with a link, 27, connecting it with a hand lever, 28, operating on a ratchet segment 29, for manual control, when it is desired to close the air shafts, 18 and 19, manually. Two corresponding groups of dampers or shutters are beneath the rearward shutters 20' and 21', but are not shown, the construction and arrangement being the same and the connections for simultaneous operation being the same.

100

Toward the bottom of the air shafts, 18 and 19, and 20 and 21, are angularly disposed fan or propeller casings, as 30, 31, 32 and 33, open in the centers of their upper sides, as at 30', 31', 32' and 33', in register with the corresponding air shafts, 18, 19, and 20 and 21. Within these casings are propellers or fans, as 34, 35, 36 and 37, on drive shafts, 38, 39, 40 and 41, anchored in suitable bearings at their lower ends in brackets, as 42, 42, and coming together at their upper ends in the top of the body, as at 43, 43, and provided with worm gears, as 44, 44, in mesh with worms, as 45, on a drive shaft, 46.

Referring particularly to Figs. 7 and 8, I will describe the driving of power mechanism. Two motors are shown, designated 47 and 48, with drive belts 49 and 50 therefrom to drive pulleys, 51 and 52 on the drive shaft, 46, above. Thus should one motor be disabled for any reason, the other would be operable or would continue to operate if both were being used at the same time. The drive shaft 46 is connected for driving a control shaft, 53, by a suitable belt connection at 54. Through these connections with the motors the propellers or fans 34, 35, 36 and 37 are driven in the air wells or shafts 18, 19, 20 and 21, for drawing air through the shutters 18', 19', 20' and 21' and also the manually operated shutters 22 and 23, these being the only ones shown, but it being understood that there are corresponding shutters beneath the shutters 20' and 21'. Either the upper or the lower shutters, in each well, can be operated for closing the same. The upper shutters are connected for automatic operation to be further described. The automatic shutters are operated through flexible members, such as cables, 55 and 56, operating over pulleys, 57 and 58, forming parts of electric clutches, as 59, shown in Fig. 5, and in Fig. 8. These electric clutches may be of any suitable type, but as shown in Fig. 5, they each comprise an armature body, 60, with winding, 61, on shaft 53, while the pulley, as 57, has a core portion, as 57', within said armature body, 60, with a coiled spring, 62, for normally separating said parts, said pulley also having one side of disc form, as 57", to engage with the face or end of said armature body, 60, when the same is energized, thus operating to drive said pulley 57 with said armature body, 60, which is secured to said shaft, 53, to turn therewith. Said armature body, 60, has connected therewith the usual commutator and brushes, as at 63, with electric wires, 64, thereto. All of these electric clutches are designated by the same numeral, 59, and are shown in Figs. 7 and 8, with the cables 55 and 56 running therefrom to the shutters 18', 19', 20', and 21'. These electric clutches are electrically controlled from a battery, B, Fig. 8, with a swinging or pendulum switch mechanism comprising a standard, 65, in which swings a pendu-

lum, 66, the upper end of which has connected thereto, a circuit wire, 67, and the lower end of which is adapted to swing into contact with four different contact segments, 68, 69, 70 and 71, having connected therewith, respectively, the electric wires, 68', 69', 70', and 71'. The upper end of the pendulum, through the wire 67 is connected to one side of the battery, B, while the four segmental contacts are connected as follows: contact 68 is connected through wire 68' to the brushes 59^a and then through line 72, to the other side of the battery B, contact 69 is connected through wire 69' to the brushes 59^b and thence through wire 73, to wire 72 and to battery B, contact 70 is connected through wire 70' with brushes 59^c and thence through wire 75 to wire 72 and to the battery. Contact 71 is connected through wire 71' to brushes 59^d and thence through wire 76 to wire 73 and thence to wire 72 to the battery B. Thus there are four electric clutches, as 59, and four pulleys controlled thereby, respectively, with cables to the four groups of shutters, with the swinging switch member, 63, operating automatically as the flying machine rocks or tilts in one direction or the other to cause the proper contact and thereby to operate the proper electric clutch and pulley to close the shutters necessary to cause the machine to right itself, that is, this swinging contact, through the electric connections and mechanisms, operates to automatically maintain the machine in a horizontal position. Said standard 65 and its swinging pendulum contact, is suspended by wires, 77 and arms 78, from the body and within the box-like body thereof in the relative position as indicated in Fig. 8, and also in Fig. 7. An electric clutch, 79, with brushes 80, is shown in Fig. 8, for electrically controlling the drive from pulley 51 and shaft 46. The wires from this clutch, 81, are extended to any suitable place for operating said clutch electrically.

Referring now to Figs. 4 and 6 in particular, there are mounted under the fixed wings, 12 and 13, in an inclined position and in substantially the planes of the fans or propellers, swinging vanes, as 82, hinged at 83, 83, and operated by means of a shaft, 84, with arms, 85, 85, and links, 86, 86, said vanes being movable into and out of a pocket, as 87, formed in the side of the body, as indicated in Fig. 6. There are four of these vanes on each side of the machine, there being one at each side of each propeller case, and operable manually from two shafts, 88 and 89, connected together for operation by means of a sprocket chain, 90 and sprocket wheels, 91, 92. The shaft 88 is provided with a hand operating wheel, 93, and said shafts 88 and 89 are connected to the vane operating shafts, as 84, by means of a worm 94 and a worm gear, 95, as clearly indicated in Figs. 4 and 6. Thus these vanes can be opened and closed manu-

70

125

130

ally as desired for the purpose of propelling the machine forwardly or rearwardly. The air from the fans or propellers being directed against said vanes, or over or outside of them, depending upon their adjusted positions.

5 Doors, as 96, are provided in the middle portion of each side for entrance of operators and passengers into the interior of the body of the machine. Pontoons, 97, 97, are also 10 provided on the under side of the machine, as illustrated, and any suitable rudder may be provided, as at 98, with means for operating the same in the usual manner.

The operation of my invention may be 15 briefly described as follows:

With the shutters 18', 19', 20' and 21' and 22, 23, 24 and 25, at the upper ends of the airshafts or wells, 18, 19, 20 and 21 all open, as shown in Fig. 4, the operation of the fans 20 or propellers 34, 35, 36 and 37 will cause a suction down through said air wells and will thereby cause the machine to rise as it sucks itself up through the air, discharging the air from the periphery of each of the fan casings. 25 When the desired height has been reached, the vanes, designated 82, may be opened as desired, depending upon which direction it is desired to travel. Or, if those on one side are open and those on the other side are closed, 30 opposed to each other, the machine can be turned around, and by reversing the vanes, the machine can be turned around in the opposite direction. I believe this will be clear from the showing made. The automatic electric control of the top groups of shutters, 18', 35 19', 20' and 21', it will be understood from the description, operates to maintain the machine on an even keel, or in a horizontal position, for if one end lowers the swinging pen- 40 dum contact will close the proper circuits to operate the opposite shutters and thus cause the machine to be righted.

I do not limit my invention to the details of construction and arrangement here shown 45 for illustrative and descriptive purposes, as I realize that many changes can be made and many different constructions and arrangements can be made to embody the principles of my invention and I do not, therefore, limit the invention to the showing made, except as I 50 may be limited by the hereto appended claims.

I claim:

1. In a flying machine a body, wings on opposite sides of said body extending longitudinally thereof, vertical air wells down through said body, propellers under said body for sucking air downwardly through said air wells, means for operating said propellers, and adjustable vanes against which said propellers discharge said air for the purpose described.

2. In a flying machine, a body, wings on opposite sides of said body extending longitudinally thereof, air wells down through said body with shutters for closing the same, pro-

pellers positioned to suck air down through said air wells when said shutters are open, means for operating said propellers, and adjustable vanes against which said propellers force the air for moving said flying machine. 70

3. In a flying machine, a body lengthwise thereof, fixed wings on opposite sides thereof, said body having air wells downwardly therethrough from the top, shutters for controlling the flow of air through said air wells, 75 propeller fans for sucking air down through said air wells, means for driving the same, said propeller fans being below said fixed wings, adjustable vanes at opposite sides of said propeller fans under said fixed wings and 80 against which said propeller fans discharge air to give movement forwardly or rearwardly to said flying machine, and means for operating said shutters.

4. In a flying machine, a body, fixed wings at opposite sides thereof, said body having air wells downwardly therethrough from the top, shutters for controlling said air wells, means for automatically opening said shutters and for closing them, said means being electric, and a swinging contact element for automatically closing the electric circuits which cause the operation of said shutters. 85

5. In a flying machine, a body, wings at opposite sides of said body, said body having a plurality of air wells down through the same from the top, shutters therein for controlling the suction of air through said air wells, propeller fans for sucking air downwardly through said air wells, and means for automatically opening and closing said shutters to maintain said flying machine in a horizontal position. 95

6. In a flying machine, a body, wings at opposite sides of said body, said body having a plurality of air wells down through the same from the top, shutters therein for controlling the suction of air through said air wells, propeller fans for sucking air downwardly through said air wells, means for manually opening and closing some of said shutters, and means for automatically opening and closing others of said shutters, and vanes adjustably mounted near said propeller fans for receiving thereagainst the air currents from said propeller fans for moving said flying machine. 105

7. In an aeroplane, a body, wings at opposite sides thereof, said body having air wells downwardly therethrough from the top, propeller fans for sucking air downwardly through said air wells whereby to decrease the atmospheric pressure above said wings and to increase it beneath said wings for lifting said aeroplane, adjustable vanes adjacent said propeller fans, under said wings, and against which said propeller fans can discharge the air for moving said aeroplane, and motor means for driving said propeller 115 120 125 130

- fans, and means for controlling the passage of air downwardly through said air wells. 13. In a flying machine, a body, supporting wings at opposite sides thereof, planes adjustable on their axes and occupying horizontally disposed positions forwardly and rearwardly of said wings, a plurality of propeller fans mounted in said body beneath said wings for sucking air down through said flying machine from the top and above said wings, adjustable vanes below said wings, and means whereby said propeller fans discharge air against said vanes for causing said flying machine to move horizontally, means for driving said propeller fans, and means for automatically maintaining said flying machine in a horizontal flying position during flight. 70 75 80
8. In a flying machine having a body and wings, means for raising and moving said flying machine including a plurality of air wells from the top downwardly through said body, propeller fans for sucking air downwardly therethrough, shutters for controlling the air flow therethrough, means for operating said shutters, and means under said wings positioned to receive air currents thereagainst from said propeller fans for moving said flying machine horizontally. 9. In a flying machine, a body, wings on opposite sides thereof convexed upwardly transversely thereof and upturned at their outer edges, planes at opposite sides of said body, forwardly and rearwardly of said wings, said body having air wells downwardly therethrough, control shutters therefor, propeller fans for sucking air downwardly through said air wells, adjustable vanes under said wings near said propeller fans and adapted to be adjusted to receive air currents thereagainst from said propeller fans for moving said flying machine horizontally, means for manually operating said control shutters, and electric means for automatically controlling said shutters, substantially as and for the purpose described. 10. In a flying machine, a body with wings, four air wells downwardly through said body from the top, shutters for opening and closing said air wells, means for operating said shutters, propeller fans for sucking air through said air wells to decrease the air pressure above and to increase it below said wings, whereby to raise said flying machine, and means for causing said flying machine to move horizontally. 11. In a flying machine, a body with wings, a plurality of air wells down through said body with shutters for controlling the passage of air therethrough, means for automatically operating said shutters to close or open said air wells, propellers for sucking air down through said air wells when open, and means for causing said flying machine to move horizontally forwardly or rearwardly. 12. In a flying machine, a body, wings on opposite sides thereof extending longitudinally thereof, said body having a plurality of air wells therethrough from the top, control shutters therein for closing and opening said air wells, means for automatically operating said shutters, said means including electric clutches and pulleys connected thereto, a source of electric energy with connections and a gravity moved contact element adapted to close certain circuits as it is moved from one position to another by gravity, propeller fans for sucking air through said air wells, means for operating the same, and means for propelling said flying machine horizontally. 13. In a flying machine including a body, wings on opposite sides of said body, planes forwardly and rearwardly of said wings, a plurality of propeller fans mounted in said body beneath said wings for sucking air down through said flying machine from the top and above said wings, adjustable vanes below said wings, and means whereby said propeller fans discharge air against said vanes for causing said flying machine to move horizontally, means for driving said propeller fans, and means for automatically maintaining said flying machine in a horizontal flying position during flight. 70 75 80 85 90 95 100 105 110 115 120 125 130
- Signed at Los Angeles, Los Angeles County, California, this 7th day of October, 1926.
